(57) **CLAIM**

The ornamental design for a sliced rectangular block of food material having one oblique longitudinal cut, as shown and described.

DESCRIPTION

FIG. 1 is a side perspective view of a sliced rectangular block of food material having one oblique longitudinal cut in accordance with the present invention;

FIG. 2 is a front end view thereof;

FIG. 3 is a back end view thereof;

FIG. 4 is a left side view thereof;

FIG. 5 is a right side view thereof;

FIG. 6 is a top side view thereof; and,

FIG. 7 is a bottom side view thereof.
